UNITED STATES PATENT OFFICE.

WILLIAM K. ACHERT, OF CINCINNATI, OHIO, ASSIGNOR TO THE UNITED STATES PRINTING AND LITHOGRAPH COMPANY, OF CINCINNATI, OHIO, A CORPORATION OF OHIO.

DISPLAY-SUPPORT.

1,252,073.

Specification of Letters Patent.

Patented Jan. 1, 1918.

Application filed February 19, 1917. Serial No. 149,422.

To all whom it may concern:

Be it known that I, WILLIAM K. ACHERT, a citizen of the United States of America, and resident of Cincinnati, in the county of 5 Hamilton and State of Ohio, have invented a new and useful Improvement in Display-Supports, of which the following is a specification.

An object of my invention is to produce 10 an improved cardboard display support for supporting tires firmly in an upright position.

This and other objects are attained in the display support described in the following 15 specification and illustrated in the accompanying drawings, in which:

Figure 1 is a perspective view of my improved display support with a tire, shown fragmentally, mounted therein.

Fig. 2 is a plan view of a cardboard blank 20 from which a display support embodying my invention is adapted to be constructed.

Fig. 3 is a fragmental side view of my improved tire support.

Fig. 4 is an end elevation of my improved tire support.

Fig. 5 is a transverse sectional view taken on line 5—5 of Fig. 3.

My improved display support consists of 30 a cardboard blank of the shape disclosed in Fig. 2, having sides 6 and 7 connected by inner walls 8 and 9 and by bottom portions 10 and 11, end flaps 12 and 13 and end flaps 14 and 15, being provided for retaining the inner walls and the sides in their folded positions. The joints between the sides 6 and 7 and the inner walls 8 and 9 are formed by lines of scoring 16 and 17, and the joints between the inner walls 8 and 9 and the bottom 35 portions 10 and 11 are formed by lines of scoring 18 and 19, scoring 16 and 17 permitting of the folding of sides 6 and 7 with relation to inner walls 8 and 9 in a direction opposite to the folding permitted by scoring 18 and 19 of the inner walls 8 and 9 with relation to the respective portions 10 and 11 of the bottom. Portions 10 and 11 in turn are connected and adapted to be folded 40 with relation to one another upon a line of scoring 20 a reinforcing strip 21 of fabric is provided for a purpose to be hereinafter more fully set forth. End flaps 12 and 13 and end flaps 14 and 15 are adapted to be 45 folded with relation to sides 6 and 7 upon lines of scoring 21, 22, 23 and 24 which per-

mit the flaps to be folded in the same direction with relation to the sides 6 and 7 that lines of scoring 16 and 17 permit the inner walls 8 and 9 to fold with relation to the sides 6 and 7. The end flaps 12, 13, 14 and 15 are provided with respective apertures 50 25, 26, 27 and 28, apertures 25 and 26 being located to register with one another when the support is folded, for the purpose of receiving a fastener 29 such as disclosed in Fig. 3, apertures 27 and 28 also being adapted to register when the support is folded to receive a similar fastening device.

In folding the support, the inner walls, 8 and 9 and the bottom portions 10 and 11 are 55 folded between sides 6 and 7 in a depending position, as disclosed in Fig. 5. End flaps 12 and 13 are then folded at right angles to sides 6 and 7 and apertures 25 and 26 are brought into registration with one another. 60 A fastener 29, such as disclosed in Fig. 3, is now passed through the registering apertures. End flaps 14 and 15 are then folded at right angles to sides 6 and 7 and apertures 27 and 28 are brought into registration 65 with one another, a fastener 29 being passed through these registering apertures to secure the flaps in their folded positions. The display support is now in condition to receive a 70 tire to be supported thereby.

As disclosed in Fig. 4 the bottom edges of the flaps 12, 13, 14 and 15 are cut at such an angle with relation to their side attaching edges, that when folded as disclosed in Fig. 4, the space between the upper edges of the 75 sides will be small enough to grasp the smallest sized tires to be supported thereby. The free edges 30, 31, 32 and 33 of the flaps, are curved so that when the flaps are folded the edges will conform to the contour of the 80 tire. The tire is supported by placing it between these curved edges and allowing it to rest upon the bottom portions 10 and 11. Larger sized tires are accommodated by moving the upper edges of the sides 6 and 7 85 apart as disclosed in dotted lines in Fig. 4, so that the tire may be placed between them. The weight of these larger sizes is such as to bring the upper edges of the sides and the 90 curved edges of the flaps into tighter gripping engagement with the sides of the tire than occurs when smaller sized tires are supported. This is essential for tires of larger 95 sizes in that it is necessary, owing to their weight and bulk, that they are supported 100 105 110

more firmly. Thus the tire itself acts directly upon the display support for providing its own firmness of support. Because of the line of scoring 20 between portions 10 and 11, the weight of the tire will cause these portions to fold with relation to one another as disclosed in dotted lines in Fig. 5, to bring the inner walls 8 and 9 into engagement with the sides of the tire. The weight of the tire will also exert a downward pull upon the top edges of the sides 6 and 7 and tend to bring these edges together and consequently bring the curved edges 30 to 33 inclusive into gripping engagement with the surface of the tire. Thus the tire will be firmly supported in an upright position.

The sides of the display support afford spaces upon which advertisements may be placed and an additional advantage is that the support may be unfolded and placed in its flattened condition as disclosed in Fig. 2, thus enabling great numbers of supports to be carried and stored away without occupying a large amount of space. The support is light, can be made of cardboard of medium weight, is cheap to manufacture, and also is amply strong for the purpose for which it is designed.

Having thus described my invention, what I claim is:

1. A display support comprising oppositely disposed sides, oppositely disposed end flaps attached to opposite edges of the sides, adapted to be connected to form ends extending from side to side, a bottom, and inner walls extending between the bottom and tops of the sides, said sides, end flaps, bottom, and walls being formed integrally and suitably distinguished from each other by scoring.

2. In a display support, the combination of a bottom, sides located on each side of the bottom, inner walls connecting the bottom and sides, end flaps secured to opposite end edges of the sides, adapted to be pivotally connected to form ends extending from side to side, whereby the sides will move into gripping engagement with an object located in the support when the object is placed between them.

3. In combination in a display support, a bottom, sides, inner walls connecting the bottom and top edges of the sides, end flaps secured to opposite end edges of the sides, adapted to be connected to form ends having their side engaging edges converging from their bottoms to their tops to hold the

sides at the inclination of the inclined edges of the end flaps, and to hold the walls substantially parallel to one another and at right angles to the supporting surface of the support, whereby a tire receiving space is provided between the walls.

4. In a tire support the combination of inner walls, a bottom between the inner walls, sides joining the inner walls, and end flaps secured to opposite end edges of the sides, adapted to be pivotally connected, whereby the sides will move into gripping engagement with an object located in the support when the object is placed between them, the inner walls being adapted to be held in engagement with the object located between them by its weight.

5. A display support comprising oppositely disposed sides, oppositely disposed end flaps attached to opposite edges of the sides, adapted to be pivotally connected to form ends extending from side to side, a bottom having a series of portions adapted to be folded with relation to one another, and inner walls extending between the bottom and tops of the sides, whereby the sides will move into gripping engagement with an object located in the support and whereby the inner walls will be moved into engagement with the sides of the object when the object contacts the bottom.

6. In combination in a display support, a bottom consisting of a series of portions adapted to be folded with relation to one another, sides, inner walls connecting the bottom and top edges of the sides, end flaps attached to opposite end edges of the sides, adapted to be pivotally connected to form ends extending from side to side and having their side engaging edges converging from their bottoms to their tops, whereby the top edges of the sides will move into gripping engagement with an object located in the support, and whereby the inner walls will move into substantially parallel positions with relation to one another and into engagement with the sides of the object when the object engages the bottom to cause its portions to fold with relation to one another.

In testimony whereof, I have hereunto subscribed my name this 16th day of February, 1917.

WILLIAM K. ACHERT.
